UNITED STATES PATENT OFFICE.

WALTER M. HOWSER, OF HAMMOND, INDIANA.

VALVE RESEATER.

Application filed July 1, 1925. Serial No. 40,910.

This invention appertains to tools and more particularly to tools utilized for refacing the valve seats of internal combustion engines and is an improvement over my 5 patent issued September 8, 1925, Number 1,552,484.

The primary object of the present invention is to provide a novel pilot or self-centering mandrel for receiving the refacing tool, so as to insure the recutting of the 10 valve seat true without chattering of the tool.

Another important object of the invention is to provide novel means for anchoring the self-centering mandrel or pilot in position on 15 the guide sleeve for the valve, so as to effectively hold the pilot or self-centering mandrel against movement and in correct axial alignment with the valve seat.

A further object of the invention is the 20 provision of a novel sleeve for receiving the refacing tool, so as to prevent play or lost movement of the sleeve radially on the pilot or self-centering mandrel.

A further object of the invention is to 25 provide novel means for connecting the refacing tool with the said sleeve, so that the same can be readily removed to allow a number of different types of tools to be associated with the sleeve.

30 A still further object of the invention is to provide a novel valve reseater of the improved character, which will permit the refacing of valve seats in an expeditious and highly satisfactory manner.

35 With these and other objects in view, the invention consists in the novel construction, arrangement and formation of parts, as will be hereinafter more specifically claimed, described, and illustrated in the accompanying drawings, in which drawings:

Figure 1 is a side elevation of the improved tool showing the same in use.

Figure 2 is a longitudinal section through the tool showing the pilot in elevation,

45 Figure 3 is a top plan view of the improved device,

Figure 4 is a detail horizontal section taken on the line 4-4 of Figure 2 looking in the direction of the arrows showing the sleeve and mandrel or pilot in section illustrating the novel formation of the sleeve to eliminate lost motion,

50 Figure 5 is a detail horizontal section taken on the line 5-5 of Figure 2 looking in the direction of the arrows through the

upper end of the sleeve, illustrating the formation of the sleeve,

Figure 6 is a detail section through the pilot or self-centering mandrel taken on the line 6-6 of Figure 2 looking in the direction of the arrows, showing the locking means for the lower end of the said mandrel or pilot in plan, and

Figure 7 is a detail section through the pilot taken on the line 7-7 of Figure 2 65 showing the cross sectional configuration of the pilot for engaging the upper end of the valve guide to facilitate the centering of the said pilot or mandrel,

Figure 8 is a view similar to Figure 2 70 taken on a smaller scale showing the screw feed head and cutting tool connected with the mandrel to bore out the valve port holes,

Figure 9 is a top plan view of the same, 75 Figure 10 is a detail section taken on the line 10-10 of Figure 8 looking in the direction of the arrows,

Figure 11 is a detail perspective view of one of the cutting blades,

Figure 12 is a detail perspective view of 80 the operating handle for the boring tool.

Referring to the drawings in detail, wherein similar reference characters designate corresponding parts, throughout the several views, the letter A generally indicates the 85 improved valve reseater and B a fragment of an internal combustion engine with which the improved tool A can be associated.

The engine B can be of the usual or any 90 preferred character and has simply been shown to illustrate the use of the tool. As disclosed the engine is provided with the usual type of valve seat 5 and guide sleeve 6 for the valve stem (not shown). When the valve seat 5 is to be refaced, the valve 95 and valve stem are removed in the ordinary manner and the improved tool A associated with the engine in lieu thereof.

The improved tool A comprises first a novel self-centering mandrel or pilot 10 100 which is adapted to be inserted through the valve seat 5 and the valve guide seat 6. This novel pilot or self-centering mandrel 10 includes an upper cylindrical body portion 11 and a lower smooth cylindrical shank 105 12 which is adapted to extend into the valve sleeve 6. The shank 12 is connected with the body 11 by a tapered portion 13 which is provided at equi-distantly spaced points with flat inclined faces 14 defining longi- 110

tudinally extending shoulders or points 15 for fitting against said sleeve. The extreme lower end of the shank 12 is provided with a reduced cylindrical extension 15, which is provided with threads 16. This cylindrical extension 15 carries novel means 17 for engaging the lower end of the valve guide 6 for cooperating with the tapered portion 13 of the pilot or self centering mandrel 10 and this means embodies a hollow cone 18 slidably mounted upon said extension, and which acts in the nature of a wedge. It is preferred to provide recesses 19 at spaced points on the outer face of the cone casing 15 to provide ribs 20 for engaging the inner face of the lower end of said valve guide of the engine and these ribs define sharp longitudinally extending edges for engaging the said sleeves in order to positively center the mandrel or pilot in place. The cone 18 is adapted to be moved into and out of locking position by means of a nut 21 which is threaded upon the thread 16 of the extension 15 and the upper face of the nut is provided with a recess 22 for receiving a head 23 formed on the lower end of the cone. If desired the upper end of the wall of the recess 22 can be upset as at 24 so as to hold the head in position. The head is of annular construction and permits free rotation of the nut relative to the cone, while at the same time sliding the cone into and out of locking engagement with the sleeve.

The improved novel tool carrying sleeve 35 of the device is indicated by the reference character 25 and at a point spaced from its upper and lower ends is provided with annular ribs 26 and 27 the outer faces of which can be serrated or otherwise roughened. The portion of the tool carrying sleeve between the annular ribs 26 and 27 is provided with diametrically oppositely longitudinal ribs 28 and 29 which can be sprung into and out of intimate contact with the body portion 11 of the mandrel to take up any lost play and screws 32 are threaded through the slit portion of the ribs 28 and 29 in order to adjust the sections 31. The upper and lower ends of the slits or slots 30 communicate with oppositely directed semi-circular slots 33 which end slightly short of the opposite ribs in order to provide connecting portions 35 and thereby prevent the entire separation of said sections 31. If preferred the slots 30 and the semi-circular slots 33 can be packed with cork or some other suitable compressible material 36 as shown.

The extreme upper end of the sleeve 25 is provided with a polygonal shaped head 37 in order to permit a wrench to be associated therewith, whereby the sleeve 25 can be rotated on the pilot, for a purpose, which will be hereinafter more fully described. The lower end of the sleeve below the annular rib or collar 27 is provided with a

threaded extension 38 and the lower face of the said collar or rib 27 is tapered as at 39 leading to said threaded extension. This threaded extension 38 is adapted to receive the novel cutting tool 40 and it is to be understood at this point that different sizes and types of cutters can be associated with the said extension. The cutter 40 as disclosed is provided with an axially threaded bore for receiving the extension and the upper and lower ends of the bore are enlarged and tapered as at 41 to provide seats for engaging the tapered portion 39 of the sleeve. One end of the cutter 40, which is of annular construction, is provided with cutting teeth 42 arranged at an angle to the longitudinal axis of the sleeve for providing the beveled valve seat. The opposite face of the cutter can be provided with teeth 43 all arranged in a horizontal plane for smoothing off the upper face of the valve seat when the same is chipped or otherwise mutilated. It is obvious that the position of the cutter can be readily reversed on the threaded extension 28 so as to bring either the teeth 42 or the teeth 43 into play.

In use of the improved device, after the valve and valve stem have been removed from the engine the pilot 10 is inserted through the valve seat into the valve sleeve 95 6 until the conical portion 13 of the pilot engages the upper edge of the said valve guide stem sleeve. The pilot is now locked in position and is effectively centered by the use of the cone 18. The desired tool 40 is 100 associated with the lower end of the valve tool carrying sleeve 25 and the sleeve 25 is then slid on the body portion of the pilot. A suitable wrench can now be applied to the sleeve and the sleeve turned until the 105 seat has been refaced. Owing to the construction of the tool carrying sleeve and the fact that the mandrel or pilot 10 is correctly centered, the valve will be refaced true and thus proper seating of the valve 110 is positively insured.

Attention is also invited to the threaded extension 45 formed on the upper end of the pilot or self-centering mandrel 10 and this extension is provided with a diametrically extending key way 46. This extension and key way is used, when it is desired to lock a different type of tool carrying sleeve or screw feed head 47 to the mandrel for boring out the valve port holes true. This 115 screw feed head 47 is provided with a smooth cylindrical bore 48 for fitting on the upper end of the mandrel and the extreme upper end of the bore is provided with a threaded socket 49 for receiving the threaded extension 45 of the said mandrel. A key 50 is employed for locking the feed head to the mandrel and the key fits in the keyway 46. The outer face of the head 47 is provided with feed screw threads 51 throughout its 130

entire length and has threaded thereon the novel boring tool 52 which will now be described. This boring tool 52 embodies a carrying collar 53 provided with internal threads for fitting upon the sleeve. The collar is provided at spaced points with suitable sockets 54 for receiving the boring blades 55 which are held at spaced points by set screws 56. The upper end of the collar is provided with the polygonal extension 57 for receiving an operating handle or crank 58. The tool is applied to the engine in the same manner as the tool heretofore described and it can be seen that as the collar 53 is rotated that the same will be fed down by the screw threads, which will effectively true the valve port holes.

Changes in details may be made without departing from the spirit or scope of this invention, but:

What I claim as new is:

1. In a valve resurfacing tool, the combination with a self-centering mandrel embodying a cylindrical body portion having a reduced cylindrical extension formed on the lower end of the body portion, and a tool carried by the body portion, the upper end of said reduced extension being provided with a tapered centering bearing portion for engaging the upper end of a valve guide stem sleeve, the surface of said tapered bearing portion provided at spaced points with flat plain faces defining longitudinal edges for biting contact with said valve guide stem sleeve, of a centering cone slidably mounted upon the lower end of the extension for engaging the lower end of said valve guide stem sleeve, the outer face of the cone being provided at spaced points with longitudinally extending ribs defining longitudinally extending edges for biting contact with said valve guide stem, and a nut rotatably carried by the lower end of the centering cone and threaded upon said extension.

2. In a valve resurfacing tool, a self-centering mandrel including a body portion adapted to extend axially through a valve seat, and a reduced extension adapted to

extend through a valve stem guide sleeve, means for locking the mandrel in a centered position in said valve stem guide sleeve, a tool carrying sleeve rotatably and slidably mounted upon said body portion of the mandrel including a main portion having annular collars formed thereon adjacent to the upper and lower end thereof, the main portion being provided with longitudinally extending ribs provided with longitudinally extending slots, the collars being provided with oppositely directed semi-circular slots communicating therewith, a compressible member fitted in said slots, take-up means extending through the ribs, a wrench engaging member formed on the upper end of the sleeve, and a tool detachably fitted on said sleeve below the lowermost collar.

3. In a valve re-surfacing tool, a self-centering mandrel including a cylindrical body portion and a reduced extension adapted to extend through a valve stem guide sleeve, means for locking and centering the mandrel against movement in said sleeve, a rotatable and slideable tool carrying sleeve fitted upon the body portion of the mandrel including a main body portion having annular collars formed therein adjacent to the upper and lower ends thereof, and longitudinally extending ribs connecting said collars, the ribs being provided with longitudinally extending slots, the collars being provided with oppositely directed spaced semi-circular slots communicating with the first mentioned slots, a compressible material in said slots, take-up means extending through the ribs, means for rotating said tool carrying sleeve, a threaded extension formed on the lower end of the sleeve below the lowermost collar, the lowermost collar having a tapered extension leading to the threaded sleeve, and a tool provided with a threaded bore for receiving said threaded extension having the opposite ends thereof tapered for engaging said tapered face and provided with cutting teeth of different types.

In testimony whereof I affix my signature.
WALTER M. HOWSER.
